UNITED STATES PATENT OFFICE.

JOHN M. BENISON, OF CAMDEN, NEW JERSEY.

DESIGN FOR A FINGER RING.

Application filed July 8, 1921. Serial No. 483,371. Term of patent 3½ years.

To all whom it may concern:

Be it known that I, JOHN M. BENISON, a citizen of the United States, residing at Camden, in the county of Camden and State of New Jersey, have invented a new, original, and ornamental Design for Finger Rings, of which the following is a specification, reference being had to the accompanying drawing, forming a part thereof.

The figure is a perspective view of a finger ring, showing my new design.

The image or picture included as a part of the invention is a symbolic representation of the protecting angel "Muriel."

I claim:

The ornamental design for a finger ring, as shown and described.

JOHN M. BENISON.
